US00D924345S

(12) **United States Design Patent** (10) **Patent No.:** **US D924,345 S**
(45) **Date of Patent:** **** Jul. 6, 2021**

(54) **GOLF CLUB HEAD**

- (71) Applicant: **PARSONS XTREME GOLF, LLC**,
Scottsdale, AZ (US)
- (72) Inventors: **Michael R. Nicolette**, Scottsdale, AZ
(US); **Bradley D. Schweigert**, Cave
Creek, AZ (US)
- (73) Assignee: **PARSONS XTREME GOLF, LLC**,
Scottsdale, AZ (US)

(**) Term: **15 Years**

(21) Appl. No.: **29/707,870**

(22) Filed: **Oct. 1, 2019**

Related U.S. Application Data

- (63) Continuation-in-part of application No. 29/687,740,
filed on Apr. 15, 2019, now abandoned.
- (51) **LOC (13) Cl.** **21-02**

U.S. Appl. No. 29/523,587, Schweigert, "Golf Club Head," filed
Apr. 10, 2015.

(Continued)

Primary Examiner — Mitchell I. Siegel

(57) **CLAIM**

The ornamental design for a golf club head, as shown and
described.

DESCRIPTION

FIG. 1 is a top perspective view of a golf club head;
FIG. 2 is a bottom perspective view of the golf club head of
FIG. 1;
FIG. 3 is a front elevational view of the golf club head of
FIG. 1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a second embodiment of
a golf club head;
FIG. 10 is a bottom perspective view of the golf club head
of FIG. 9;
FIG. 11 is a front elevational view of the golf club head of
FIG. 9;
FIG. 12 is a rear elevational view of the golf club head of
FIG. 9;
FIG. 13 is a top view of the golf club head of FIG. 9;
FIG. 14 is a bottom view of the golf club head of FIG. 9;
FIG. 15 is a left side view of the golf club head of FIG. 9;
and,
FIG. 16 is a right side view of the golf club head of FIG. 9.
The broken lines shown on the drawing figures form no part
of the claimed design.

1 Claim, 14 Drawing Sheets
